SWING

Charley H. Williams, El Reno, Okla.

Application January 11, 1940, Serial No. 313,452

1 Claim. (Cl. 155—58)

This invention relates to an improved swing and seeks, among other objects, to provide a device of this character which will be particularly adapted for use by children on playgrounds.

Another object of the invention is to provide a swing which is capable of use in three different ways for providing amusement and exercise.

A further object of the invention is to provide a swing wherein improved means is employed for effecting support of said swing at its opposite ends.

A further object of the invention is to provide a swing having a seat or bar in the form of a single pole, which pole may, if desired, be coated with rosin or the like to prevent slipping.

As a still further object, the invention seeks, in a modified embodiment, to provide resilient supporting means for the seat or bar.

Other objects of the invention not mentioned hereinbefore will become apparent during the course of the following description.

In the drawing forming a part of my application:

Figure 1 is a side elevation of my improved swing,

Figure 2 is a vertical sectional view on the line 2—2 of Figure 1 looking in the direction indicated by the arrows.

Figure 2^a is an enlarged vertical sectional view of one of the ball and socket members,

Figure 3 is a detail elevation showing a slightly modified embodiment of the invention, and

Figure 4 is a detail elevation showing a slightly modified head construction.

Referring now more particularly to the accompanying drawing, wherein like reference numerals designate similar parts throughout the views, the numerals 1 and 2 indicate in general end supports which form a part of my swing. The end supports 1 and 2 are of identical construction so that a description of one will suffice for both. As will be seen in Figure 1, the end supports 1 and 2 are located in opposing, or facing, spaced relation. The support 1, for example, includes side members 3 and 4 which are inclined outwardly toward their lower ends. The support 1 also includes a rearwardly inclined supporting member 5. It will be seen that the support 1 is, therefore, of substantially triangular shape in side elevation. The members 3, 4 and 5 are connected at their corresponding ends by a head 6 which is of one-piece construction and includes sockets 7 for receiving the upper ends of said members 3, 4 and 5. The sockets 7 are, of course, disposed in a downward direction and

in the proper position for receiving the members. The head 6 also includes a horizontally disposed socket 8 which is for the purpose of receiving one end of a suspension bar 9. The suspension bar 9, as clearly seen in Figure 2, is of hollow construction and extends between the supports 1 and 2, being anchored in the socket 8 of the head 6 of each of the supports.

A cylindrical swing seat or bar is indicated at 10. The bar 10 is relatively large and is of circular formation in cross section. The bar may be of solid wood construction or of hollow metal construction, as desired. The bar 10 has a pair of annular bands or clips 11 surrounding the same in spaced relation to the opposite ends of the bar. The clips 11 are each provided with an attaching ring 12. As best shown in Figure 2^a of the drawing, a ball and socket member 13 and 13' is mounted on the suspension bar 9, the socket member being provided with a bolt 13'' which extends through the suspension bar 9 for engagement with a nut 14. As will be seen, one of the ball and socket members is mounted on the suspension bar 9 near each end thereof. Downwardly converging chains 15 connect the attaching rings 12 with the ball members 13 so that the bar 10 will be mounted for swinging movement on the suspension bar 9.

When my improved swing is in operation, it is capable of use in three different ways. First, the bar may be swung back and forth in an arc at right angles to the length of the swing. Any desired number of persons may swing upon the bar 10 as desired, depending entirely on the length of the bar. Second, the bar 10 may be swung endwise. That is to say, through an arc on substantially the same plane with the length of the swing. When the device is used in this manner, as many persons as desired may be supported on the bar 10. The third possible manner of using the swing is as follows: A person may be seated on the bar 10 at the center thereof and, by an upward swing and sidewise twist, cause the swing to spring up and down and twist from side to side. This movement will simulate that of a balking horse. When the device is being used in this manner, a child can exercise his or her legs and body in a highly effective manner. The device will, of course, be entertaining to children.

In the slightly modified embodiment of the invention shown in Figure 3, the numeral 16 indicates the suspension bar and the numeral 17 the seat bar. The suspension bar 16 carries a bolt 18 which has mounted on its lower end a ball

and socket member 19 similar in construction to the ball and socket member shown in Figure 2^a of the drawing. A nut 20 is carried on the upper end of the bolt. A spring 21 surrounds the bolt 18 between the nut 20 and the bar 16. A bolt 21^a is passed through the end of the bar 10 and is provided with a terminal head perforated transversely to form an attaching eye or ring 22. A nut 23 is carried at the lower end of the bolt, and said bolt has a spring 24 thereabout and between the nut 23 and the lower surface of the bar 10. A chain 25 extends between the eye of the head 22 and the ball and socket member 19. The springs 21 and 24 will, in use, provide greater resilience for the bar 10 so that, when the device is being used by one person to simulate a balking horse, greater springing action will be assured. Attention is directed to the fact that the bar 10 may be covered with rosin or wax, or left plain, as desired.

As shown in Figure 4, the head 6 may be of multi-section construction. That is to say, the head of this embodiment includes sections 6^a and 6^b which are adapted to be connected to mating sections on the opposite side of the head so that said head will include four sections or elements. The sections 6^a are connected to their mating diametrically disposed portions by a bolt 6^c and

the sections 6^b are connected to their diametrically disposed sections by bolts 6^d. The sections 6^a and 6^b, together with their corresponding mating sections, are connected together by a bolt 6^e.

Having thus described the invention, what is claimed as new is:

A swing comprising spaced supports, a suspension bar connecting said supports, an elongated cylindrical seat member, bolts extending transversely through the opposite ends of the seat member and having their upper ends provided with attaching eyes and their lower ends threaded, nuts engaging the threaded ends of the bolts, springs interposed between the nuts and said seat member, ball and socket members mounted on the suspension bar, and downwardly converging chains having their lower ends connected with the attaching eyes and their upper ends operatively connected with the ball and socket members, said seat member being mounted on the suspension chains to move in an arc at right angles to the vertical plane of the length of said suspension bar or in the same vertical plane therewith and being shiftable upwardly and twistable sidewise to simulate a balking horse.

CHARLEY H. WILLIAMS.
